WORK POSITIONING APPARATUS

Leo Meister, Irvington, N. J.

Application September 18, 1942, Serial No. 458,907

5 Claims. (Cl. 86—1)

(Granted under the act of March 3, 1883, as amended April 30, 1928; 370 O. G. 757)

The invention described herein may be manufactured and used by or for the Government for governmental purposes, without the payment to me of any royalty thereon.

This invention relates to work positioning apparatus such as used in mass production to hold a work-piece in position while the tool performs its operation on the work. It deals particularly with the handling of explosive charges in ammunition manufacture.

Work in ammunition factories is constantly painstaking and time consuming because of the necessity for care in the handling of explosive ingredients and mixtures. Efforts are continually being made to eliminate the human factor in the handling of explosives, because human practice is most likely to vary from a safe and established procedure. The loading of primer cups is one of the many phases of explosive manufacture which require care in handling, and in which speed is also important.

It is an object of this invention to provide apparatus to aid in positioning and holding a primer cup loading adapter while it is being operated on by a tool such as a compressing plunger, and to facilitate in releasing the adapter from that position when the compressing operation has been completed. However, the apparatus is not limited to such an application.

This object is achieved by an indexing member consisting of a block having a V-shaped recess to receive the adapter. An electromagnet at the vertex of the V is energized when a cam on the plunger closes a switch as the plunger approaches the adapter. The switch is held closed until the plunger again withdraws, when another cam trips a switch to momentarily energize a second electromagnet, positioned along one side of the V, to pull the adapter out of the operating position into a position where it can be engaged by hand with comparative safety.

The specific nature of the invention as well as other objects and advantages thereof will clearly appear from a description of a preferred embodiment as shown in the accompanying drawing in which:

Fig. 1 of the drawing shows the work positioning apparatus of the invention and its connections in the electrical control circuits.

Fig. 2 is a plan view of the recessed platen with its cover plate removed.

Fig. 3 is a longitudinal center section through the platen and cover member.

Fig. 4 is a longitudinal center section through

the platen, showing the cover separated from the recessed member.

Fig. 5 is a perspective view of the recessed platen, with the cover member removed.

5 Referring to the drawing in detail, a work positioning member 2 is shown as made up of a recessed platen 4 and a cooperating cover member 6, held to a supporting table 8 by screws 10. Screws 10 preferably extend upward from the underside of the table, and preferably do not extend through to the upper side of the indexing member, to avoid small cracks or recesses where a dangerous concentration of powder might accumulate.

10 Platen 4 has a holding recess or stop 12 which is generally V-shaped as seen from above. A recess 14 which has, preferably, the general shape of a horseshoe is provided at the vertex of the V-shaped stop, and a second horseshoe recess 16 is provided in one side of the V of the stop. Electromagnets 18 and 20 are disposed in recesses 14 and 16 respectively; magnet 18 serves as a holding magnet and magnet 20 serves as a moving magnet, as will be shown.

15 The leads for magnet 18 are connected to switch 22, and the leads for magnet 20 are connected to switch 24. A compressing plunger 26 carries cams 28 and 30 to close switches 22 and 24, respectively. Any suitable electric power source 32 may be provided to energize the magnets. Plunger 26 will, of course, have the desired shape of the tool required for the work to be done. In the present case, this tool is a plunger, as shown, for operation on a primer cup loading adapter, such as the one shown at 34, which is in position to be operated upon by the plunger when it is in firm contact with both sides of the V-shaped stop.

20 Cover member 6 has projections 36 which fit into the horseshoe shaped recesses to hold the magnets in place.

25 Operation.—Switch 24 will preferably be one which is closed only by movement of cam 30 past the switch in the upward direction. Therefore, when the adapter 34 is put approximately in place by being pushed manually into the V, movement of plunger 26 downward will not energize magnet 20, thus magnet 20 will not disturb the positioning of the adapter. As the plunger continues to advance downward, cam 28 closes switch 22, energizing magnet 18, which remains energized during the powder compressing action, securely holding the adapter in place. Furthermore, the effect of the magnet is to hold the adapter down, as well as tight in against the

V, so that the adapter is securely and effectively held in place during withdrawal of the plunger. As the plunger continues to rise, cam 28 moves out of engagement with switch 22, and magnet 18 is deenergized. With continued upward movement of the plunger, cam 30 trips switch 24, momentarily energizing magnet 20. This momentary energization of magnet 20 gives an impulse to adapter 34, pulling it in the direction of the magnet. However, since the magnet is energized only momentarily, the adapter is free to slide past the magnet by virtue of its inertia. It is then in a position where it may be safely and securely grasped with the fingers for removal.

If the design of the machine is such that the plunger does not permit the addition of cams, the same results may also be obtained by connecting two switches in the same circuit, but working with the movement of a foot pedal. On the down movement of the foot pedal a switch is closed energizing center magnet, and on the up movement the outer magnet is energized. The pedal is normally in switch off position.

It will be noted that the work supporting portion of the platen presents a smooth imperforate surface, there being no openings in which powder dust might accumulate, and possibly cause trouble.

I claim:

1. Apparatus for positioning and holding a work piece of magnetizable material, comprising a work supporting platen having a reentrant V-shaped stop, a recess in the platen adjacent the vertex of the stop, a magnet in said recess and arranged to exert its attractive forces at the said vertex of the stop to position and hold the work, a second magnet to one side of the vertex of the stop exerting its attractive forces in a region removed from the said vertex to remove the work from said vertex, and means for alternately energizing and deenergizing the magnets for the purpose specified.

2. The invention of claim 1, characterized in that the means for alternately energizing and deenergizing the magnets, comprises a reciprocating tool having two cams thereon, a source of electric energy for each magnet, an electric circuit for each magnet, a switch in each circuit, one controlling the positioning and holding magnet, and the other the work removing magnet, one cam operating upon the switch for energizing

the holding magnet, and the other cam operating upon the other switch upon the withdrawal of the tool to deenergize the work holding magnet and energize the work removing magnet.

5. 3. Apparatus for positioning and holding a work piece of magnetizable material, comprising a work supporting platen having a reentrant V-shaped stop, a recess at the vertex of the stop, magnetic means in said recess arranged to exert its attractive forces in the region of the said vertex to hold the work in operative position at said vertex, a tool movable to operate upon the work, means carried by the tool for making the first mentioned means effective, another magnetic means in a region removed from the said vertex and also arranged to exert its attractive forces in a region removed from said vertex to remove the work from operative position in the said vertex, and means carried by the tool to render said first 10 means ineffective upon the withdrawal of the tool and the second means effective to remove the work from operative position.

4. An apparatus for positioning and holding a work piece of magnetizable material, comprising 25 a work supporting platen having a reentrant V-shaped stop, a work-holding and positioning magnet in the platen near the vertex of the recess and exerting its attractive forces in the region thereof, a work removing magnet alongside the 30 first and also exerting its attractive forces along the sides of the stop to remove the work piece from said vertex, a source of electric energy, an electric circuit for each magnet and a normally open switch in each circuit, a reciprocating tool 35 for operating upon the work piece and means actuated by the tool to control the switches to alternately energize and deenergize the magnets.

5. Apparatus for positioning and holding a work piece of magnetizable material, comprising 40 a platen having a reentrant V-shaped stop, magnetic means in the platen exerting its attractive forces at the vertex of said stop for positioning and holding the work piece in operative position of said vertex, another magnetic means exerting 45 its force along a side of said stop to remove the work from operative position, means for energizing the work holding magnet, and means for energizing the work removing magnet, said means being separate and operating to energize the removing magnet after deenergizing the holding magnet.

LEO MEISTER.
